US0D1000983S

(12) **United States Design Patent** (10) Patent No.: **US D1,000,983 S**
Gao (45) Date of Patent: ** Oct. 10, 2023

(54) **VEHICLE DIAGNOSTIC DEVICE**

(71) Applicant: **AUTEL INTELLIGENT TECHNOLOGY CORP., LTD.**,
 Guangdong (CN)

(72) Inventor: **Ming Gao**, Guangdong (CN)

(73) Assignee: **AUTEL INTELLIGENT TECHNOLOGY CORP., LTD.**,
 Guangdong (CN)

(**) Term: **15 Years**

(21) Appl. No.: **29/760,579**

(22) Filed: **Dec. 2, 2020**

(30) **Foreign Application Priority Data**

Jun. 5, 2020 (CN) 202030280474.2

(51) **LOC (14) Cl.** **10-04**

(52) **U.S. Cl.**

USPC **D10/78**

Primary Examiner — George D. Kirschbaum
 Assistant Examiner — Antoinette Martine Suiter

(57) **CLAIM**

I claim the ornamental design for a vehicle diagnostic device, as shown and described.

DESCRIPTION

FIG. 1 is a front elevational view of a vehicle diagnostic device showing my new design;

FIG. 2 is a back elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a front, right perspective view thereof; and,

FIG. 8 is a back, left perspective view thereof.

1 Claim, 4 Drawing Sheets
